APPARATUS FOR HANDLING BARS

Myles Morgan, Worcester, Mass., assignor to
 Morgan Construction Company, Worcester,
 Mass., a corporation of Massachusetts

Application March 31, 1949, Serial No. 84,599

7 Claims. (Cl. 198—219)

1

This invention relates to apparatus for handling bars, and more particularly to conveying mechanism for handling metal bars such as billets, slabs, and the like.

In the art of rolling metal it is a common practice to heat metal bars, such as steel billets or slabs, to a suitable rolling temperature in a furnace, from which they are discharged one at a time to the first stand of a rolling mill. The bars to be heated are deposited in a mass or pile near the furnace, usually by means of a crane, and this pile must be broken up and unscrambled so that one bar at a time may be delivered to the furnace. In the past this separation has required very arduous manual labor on the part of several workmen armed with tongs, hooks, and other hand tools. Such work is not only difficult and expensive, but also dangerous because of the possibility the pile of bars may slide and avalanche without warning.

The problem has been recognized, and an attempt at its solution is disclosed in the United States patent to Quinn, No. 1,889,039, granted November 29, 1932. The patented apparatus effected a reduction in the amount of manual labor required but it by no means eliminated such labor entirely. Considerable power was needed for its operation, and it was found that slabs could not be handled satisfactorily, since they would travel along one on top of the other.

It is accordingly one object of the invention to provide a dependable power actuated apparatus capable of breaking up a pile of metal bars and delivering them one at a time without any need of manual labor.

It is a further object of the invention to provide an improved conveying apparatus adapted to receive a group of metal slabs piled one on top of another, and capable of separating the slabs and delivering them one at a time.

It is a further object of the invention to provide a power actuated bar separating and conveying apparatus which will be highly efficient in its use of power.

With these and other objects in view, as will be apparent to those skilled in the art, the invention resides in the combination of parts set forth in the specification and covered by the claims appended hereto.

Referring to the drawings illustrating one embodiment of the invention and in which like reference numerals indicate like parts,

Fig. 1 is a plan view of a bar handling apparatus, with certain parts broken way for clearness of illustration;

2

Fig. 2 is a section through the apparatus on a somewhat larger scale than Fig. 1, the section being taken on the line 2—2 of Fig. 3;

Fig. 3 is a section taken on the line 3—3 of Fig. 2;

Fig. 4 is a view showing one of the upper moving skids with its supporting and driving means;

Fig. 5 is a view showing one of the stationary skids and its supports;

Fig. 6 is a view showing one of the lower moving skids with its supporting and driving means; and

Figs. 7 to 17 inclusive are diagrammatic side elevations of the apparatus showing the progressive movement of slabs along the same.

As shown particularly in Fig. 1, the embodiment illustrated comprises a substantially horizontal conveyor 20 of known construction having spaced horizontal rollers 21 driven by a main shaft 22 through bevel gearing 23, the shaft 22 being driven by a suitable source of power (not shown) under the control of the operator. A plurality of stationary skids 25 extend from one side of the conveyor 20 and at right angles therewith. These skids are preferably spaced several feet horizontally from one another, and the number required will depend upon the length of the longest bars to be handled. If four skids are provided as shown, and they are spaced at intervals of approximately eight feet, bars thirty feet long may be readily handled. As best shown in Fig. 5, the front end of each skid 25 (i. e. the end adjacent the conveyor 20) rests on a beam 26, and the rear end of each skid 25 extends into a housing 27 and rests on a plate 28. Two intermediate supports 30 and 31 are also provided for each skid. The rear portion of each skid 25 is provided with a substantially horizontal upper surface 32, which may be described as the receiving surface of the skid, since the pile of bars may be deposited thereon initially by a crane or other suitable means. In front of the receiving surface 32 there are provided on each skid three successively lower substantially horizontal upper surfaces 33, 34, and 35. An inclined surface 37 extends downwardly and forwardly from the receiving surface 32 to the surface 33. An inclined surface 38 extends downwardly and forwardly from the surface 33 to a point slightly below the surface 34 and connected thereto by a shoulder 39 which preferably is perpendicular to the surface 38 to form a shallow right-angled notch 40. Similarly, an inclined surface 42 extends downwardly and forwardly from the surface 34 to a point slightly

below the surface 35 and connected thereto by a shoulder 43 which preferably is perpendicular to the surface 42 to form a shallow right-angled notch 44. An inclined surface 45 extends downwardly and forwardly from the surface 35 in position to direct bars onto the conveyor rollers 21.

Means is provided for moving bars broadside in a forward direction along the skids 25. For this purpose an upper moving skid 46 is located at one side of each stationary skid 25, the top surface of each skid 46 being shaped to provide a substantially horizontal rear portion 47 (Fig. 4) and a substantially horizontal front portion 48 which is the same distance below the surface 47 as the surface 33 of the stationary skid 25 is below the surface 32 thereof. The two surfaces 47 and 48 are connected by an upright shoulder 49. The front edges of the two surfaces 47 and 48 are located near the front edges of the surfaces 32 and 33 respectively of the stationary skid, as best shown in Fig. 2. The rear end of each skid 46 extends into the adjacent housing 27 and rests on a transverse roller 51 which is supported by the plate 28. The skids 46 are supported near their front ends on a transverse horizontal beam 52 to which they are suitably secured, and this beam in turn is fastened to the upper ends of two spaced upright struts or columns 53. The lower ends of the struts 53 are pivotally connected to a pair of spaced aligned eccentrics 54 which are formed integral with a main horizontal shaft 55 (Fig. 3) rotatably supported in bearings 56. A reversible electric motor 58 (Fig. 1) is connected to the shaft 55 through a suitable speed-reducing mechanism 59. These various parts are so constructed and arranged that as the shaft 55 is rotated, the eccentrics 54 will cause points on the tops of the skids 46 to travel in closed paths, with approximately half of each path above and half below the tops of the stationary skids.

A lower moving skid 61 is located at one side of each stationary skid 25, preferably on the opposite side thereof from the corresponding upper moving skid 46. Each of these lower moving skids 61 has a top surface shaped to provide an approximately horizontal rear portion 62 (Fig. 6) and an approximately horizontal front portion 63 which is the same distance below the surface 62 as the surface 35 of the stationary skid 25 is below the surface 34 thereof. At the front of the surface 62 there is provided a shoulder 64 which leads downwardly to a recess 65 located behind the surface 63 and connected thereto by a short rearwardly facing shoulder 66. The front edges of the surfaces 62 and 63 are located near the front edges of the surfaces 34 and 35 respectively of the stationary skid, as best shown in Fig. 2. The front end portion 68 of each skid 61 is considerably lower than the surface 63 and extends beneath the conveyor 20. This portion 68 rests upon a transverse roller 69 which is supported by a plate 70. The rear ends of the skids 61 are supported on a transverse horizontal beam 72 to which they are suitably secured, and this beam in turn is fastened to the upper ends of two spaced upright struts or columns 73. The lower ends of the struts 73 are pivotally connected to a pair of spaced aligned eccentrics 74 which are formed integral with the shaft 55. The eccentrics 74 are displaced 180 degrees with respect to the eccentrics 54, or in other words the two pairs of eccentrics are located on diametrically opposite sides of the axis of the shaft 55. Furthermore the throw of the eccentrics 74 is much greater than

that of the eccentrics 54 and preferably about twice that of the latter. In one particular embodiment of the invention a throw of $1\frac{1}{4}$ inches has been provided for the eccentrics 54, and a throw of $2\frac{1}{2}$ inches for the eccentrics 74, thus providing horizontal movements of $2\frac{1}{2}$ inches and 5 inches for the upper and lower skids respectively. The surfaces 62 and 63 are parallel with one another, but they have a downward and rearward inclination, particularly when the eccentrics 74 are in their lowermost positions, as shown in Fig. 2. This inclination is preferably such that while a point on the front edge of the surface 63 moves equal distances above and below the surface 25 during the rotation of the shaft 55, a point on the surface 62 moves a less distance above the surface 34 than below the same. Consequently the amount of horizontal travel imparted to a bar at each rotation of the shaft 55 will increase continuously as the bar progresses forwardly along the surface 34 and 35. This aids in obtaining the desired separation of bars as they approach the conveyor 20.

In order to make possible the required control over the bars, I preferably provide retractable means or abutments for blocking forward travel of the bars along the upper or receiving surfaces 32 of the stationary skids 25. For this purpose bell crank levers 76 (Fig. 2) are fulcrumed on certain of the skids 25 by means of pins 77, these levers having upwardly projecting hooks 78 thereon. Fluid actuated motors 80 are connected to the levers 76 so that the levers may be turned about the pins 77, under the control of the operator, to move the hooks 78 either above or below the skid surfaces 32.

The operation of the invention will now be described. While bars of many different shapes and sizes may be handled, slabs present much greater difficulties than billets. Not only do slabs tend to travel along broadside one on top of the other, which is not so serious a problem with billets, but the slabs are often much heavier than billets. Thus a steel slab 2 inches thick, 16 inches wide, and 30 feet long will weigh approximately 3220 pounds. This is a comparatively small slab, and yet it obviously cannot be shifted around very readily by manual labor. For these reasons, in the description of the operation, the emphasis will be placed upon the handling of slabs.

Referring first to Fig. 2, a group of fifteen slabs has been shown as deposited on the apparatus by suitable means, such as an overhead crane (not shown). Since the upper moving skids 46 are shown in their raised positions, the slabs are resting upon them, but if these skids were in their lowered positions the slabs would of course rest upon the surfaces 32 of the stationary skids 25. While the slabs may be grouped in various ways, they are shown arranged in three laterally adjacent piles with five slabs in each pile. The operator will first raise the hooks 78 by means of the motors 80 and then start the main shaft 55 rotating in a forward direction. At each rotation of the shaft, the skids 46 will lift the slabs, carry them forwardly, and set them down on the stationary skids 25. As the group of slabs reaches the raised hooks 78, further forward travel will be blocked, and the slabs will be "squared up" or brought into exact right-angular relationship with the skids, whereupon the operator will lower the hooks 78. As the rotation of the main shaft continues, the advancing movement of the entire group of slabs will continue until the first pile of slabs slides down the in-

cline 37 onto the surface 33, as indicated in Fig. 7. At this point it is desirable to raise the hook 78 again, and hold back the two remaining piles in order to effect a better separation of the slabs. It will be noted that the two topmost slabs 1 and 2 of the first pile have slid along the surface 33, while the three remaining slabs 3, 4 and 5 of this pile have "shingled" forwardly and are partially supported one on the other. Upon continued operation of the apparatus, the first slab 1 will slide down the incline 38 and drop into the notch 40, as shown in Fig. 8. This will take place when the upper skids 46 are raised and moving forwardly. Since the eccentrics 74 are displaced 180 degrees from the eccentrics 54, the lower skid 61 will at this same instant be lowered and moving rearwardly, hence the surface 62 thereof will be below the notch 40 and will not interfere with the entrance of the slab into this notch. Once a slab has reached the notch 40, it will from then on be under the control of the lower skids 61 rather than the upper skids 46. In Fig. 9 the lower skids have moved the first slab 1 out of the notch 40 and along the stationary skid surface 34 nearly to the end thereof, while the upper skids have deposited the slab 2 in the notch 40. In Fig. 10 the lower skids have moved the slab 2 out of the notch 40 and deposited the slab 1 in the notch 44. By this time the upper skids 46 have advanced the three shingled slabs 3, 4 and 5 an appreciable distance along the skid surface 33, and the operator will lower the hooks 78 to release the second pile of five slabs. In Fig. 11 the lower skids 61 have lifted the slab 1 out of the notch 44 and along the surface 35, and they have moved the slab 2 along the surface 34. Meanwhile the upper skids 46 have advanced the slab 3 so that it has dropped into the notch 40, and they have advanced the second pile of slabs until they have slid down the incline 37 in a forwardly shingled formation and been stopped by engagement with the slab 5, which was originally at the bottom of the first pile. The hooks 78 have again been raised in order to hold back the third pile of slabs. In Fig. 12 the slab 1 has slid down the incline 45 onto the conveyor rollers 21, which will be placed in operation to deliver the slab longitudinally to a heating furnace or other apparatus associated with the conveyor. Ordinarily the movement of the skids 46 and 61 will be stopped during the operation of the conveyor rollers 21. In Fig. 13 the hooks 78 have been lowered, all the slabs have been moved forwardly by the action of the moving skids, and the third pile of slabs is slightly overhanging the rear edge of the surface 32. In Fig. 14 the third pile of slabs has slid down the incline 37 in the desired forwardly shingled formation. The slab 6, which was originally the top slab of the second pile, has dropped into the notch 40. In Fig. 15 the slab 2 has reached the conveyor rollers 21, and the slab 4 has slid down the incline 42 and been stopped by its engagement with the shoulder 66 of the moving skid 61, which is in its raised position such as to overlap the notch 44. The slab 6 has been lifted out of the notch 40 and has slid forwardly into contact with the slab 5. At any time now additional piles of slabs may be placed on the receiving surface 32, although such additional piles have not been illustrated. In Fig. 16 the slab 5 has dropped into the notch 44, the slab 7 has caught up with the slab 6 (by sliding forwardly as it is lifted out of the notch 40), the slab 8 has dropped into the notch 40, and the slab 9 is resting flatwise on the slab 10, which

is supported on the surface 48 of the upper moving skid. In Fig. 17 the slab 3 has reached the conveyor roller 21, the slab 6 has descended to the surface 35, and the slab 8 has moved from the notch 40 onto the surface 34. The slab 10, with the slab 9 supported thereon, has dropped into the notch 40 and been stopped abruptly by its engagement with the shoulder 39 thereof, while gravity and the momentum of the superimposed slab 9 has caused the latter to slide forwardly relative to the slab 10 and into contact with the slab 8 in front thereof. By the continued operation of the moving skids, slabs may be deposited one at a time on the conveyor rollers 21. If at any time a slab becomes skewed with respect to the skids, it can be squared up by rotating the main shaft 55 in the reverse direction to move the skewed slab back against the nearest inclined surface 37, 38 or 42 in the rear thereof. During the forward travel of the slabs, each slab will be automatically squared up with the skids whenever it drops into the notches 40 or 44. At the same time any superimposed slab will be carried forwardly by gravity and its own momentum as the lower slab is suddenly stopped, so that the desired separation of the slabs may be brought about.

The length of the inclined surfaces 38 and 42 is not critical, but it is preferably greater than half the width of the slabs to be handled, so that the slabs may engage the shoulders 39 and 43 properly. The width of these shoulders is preferably less than the thickness of the slabs to be handled, so that only one slab at a time will be retained by the shoulders. The surfaces 37, 38 and 42 are sufficiently inclined to ensure downward sliding of the slabs over the same. If the lower moving skids 61 are in their raised positions when a bar slides down the surfaces 42, so that the notches 44 are rendered ineffective to stop such bar, it will nevertheless be stopped by its engagement with the shoulders 66, as shown in Fig. 15. The opposed relationship of the eccentrics 54 and 74 helps to balance and reduce the load on the driving motor, for during such time as the eccentrics 54 are lifting the upper skids 46 and the bars thereon, the eccentrics 74 will be lowering the lower skids 61 and the bars thereon, and vice versa. The increased throw of the eccentrics 74, as compared with the throw of the eccentrics 54, provides a greater step-by-step travel for the bars along the front portions of the stationary skids than along the rear portions thereof. This is important in obtaining the desired separation of the bars so that they may be delivered one at a time to the conveyor rollers 21.

It will be apparent that the invention makes it possible to handle heavy metal bars in a very efficient manner without requiring any appreciable manual labor. Even superimposed slabs can be separated from one another. While two sets of moving skids are employed, they are driven from a common shaft, so that the manufacturing cost of the apparatus is not excessive.

Having thus described my invention, what I claim as new and desire to secure by Letters Patent is:

1. Apparatus for handling bars comprising a plurality of horizontally spaced parallel stationary skids adapted to support generally horizontal bars extending transversely thereof, each skid being shaped to provide two bar-supporting surfaces one of which is in front of the other and at a lower elevation, upper moving skids laterally adjacent to the upper bar-supporting surfaces

of the stationary skids, lower moving skids laterally adjacent to the lower bar-supporting surfaces of the stationary skids, a horizontal rotatable shaft extending transversely beneath the stationary skids, eccentrics on the shaft, means pivotally connecting the front portions of the upper moving skids to the eccentrics, other eccentrics on the shaft, means pivotally connecting the rear portions of the lower moving skids to the said other eccentrics, means supporting the rear portions of the upper moving skids, and means supporting the front portions of the lower moving skids.

2. Apparatus as set forth in claim 1, in which the first mentioned eccentrics are displaced approximately 180 degrees from the said other eccentrics.

3. Apparatus as set forth in claim 1, in which the throw of the first mentioned eccentrics is appreciably less than that of the said other eccentrics.

4. Apparatus as set forth in claim 1, in which each stationary skid also has an inclined surface leading downwardly and forwardly from the upper surface to a notch slightly below the level of the lower surface, and in which the first mentioned eccentrics are displaced approximately 180 degrees from the said other eccentrics, so that when the upper moving skids are raised and traveling forwardly to start a bar down the said inclined surfaces the lower moving skids will be beneath the notches and the notches will be open to receive the bar.

5. Apparatus for handling bars comprising a plurality of horizontally spaced parallel stationary skids adapted to support generally horizontal bars extending transversely thereof, each skid being shaped to provide four bar-supporting surfaces positioned successively one in front of the other and at successively lower elevations, upper moving skids laterally adjacent to the stationary skids and arranged to move bars broadside forwardly with a step-by-step movement along the first or uppermost and the second bar-supporting surfaces, lower moving skids laterally adjacent to the stationary skids and arranged to move bars broadside forwardly with a step-by-step movement along the third and fourth bar-supporting surfaces, a horizontal rotatable shaft extending transversely beneath the stationary skids, two aligned eccentrics on the shaft, means pivotally connecting the front portions of the upper moving skids to the eccentrics, two other aligned eccentrics on the shaft having an appreciably

greater throw than the first mentioned eccentrics and displaced approximately 180 degrees therefrom, means pivotally connecting the rear portions of the lower moving skids to the said other eccentrics, means supporting the rear portions of the upper moving skids, and means supporting the front portions of the lower moving skids.

6. Apparatus as set forth in claim 5, in which each stationary skid is shaped to provide an inclined surface leading downwardly and forwardly from the first bar-supporting surface to the second bar-supporting surface, an inclined surface leading downwardly and forwardly from the second bar-supporting surface to a notch slightly below the level of the third bar-supporting surface, and an inclined surface leading downwardly and forwardly from the third bar-supporting surface to a notch slightly below the level of the fourth bar-supporting surface, and in which the upper surface of each lower moving skid is provided with a rearwardly facing shoulder located adjacent to the last-mentioned notch and arranged to stop bars sliding down the last-mentioned inclined surfaces when the lower moving skids are in the upper portion of their travel orbit.

7. Apparatus for handling bars comprising a plurality of horizontally spaced parallel stationary skids adapted to support generally horizontal bars extending transversely thereof, each skid being shaped to provide two bar-supporting surfaces one of which is in front of the other and at a lower elevation, upper moving skids associated with the stationary skids and constructed to move bars broadside forwardly along the upper surfaces with a step-by-step movement, lower moving skids separate from the upper moving skids associated with the stationary skids and constructed to move bars broadside forwardly along the lower surfaces with a step-by-step movement, and driving means for the moving skids such that the lower moving skids will produce an appreciably greater movement of the bars than the upper moving skids.

MYLES MORGAN.
